DESIGN FOR A SINGLE SPINDLE AUTOMATIC METAL WORKING MACHINE

Alfred E. Drissner, Cleveland, Ohio, assignor to
The National Acme Company, Cleveland, Ohio,
a corporation of Ohio

Application June 7, 1945, Serial No. 119,955

Term of patent 14 years

(CL D54—6)

To all whom it may concern:

Be it known that I, Alfred E. Drissner, a citizen of the United States, residing at Cleveland, in the county of Cuyahoga and State of Ohio, have invented a new, original, and ornamental Design for a Single Spindle Automatic Metal Working Machine, of which the following is a specification, reference being had to the accompanying drawing, forming part thereof.

The figure is a perspective view of a single

spindle automatic metal working machine showing my new design. The end, not shown, is substantially plain and the side opposite to that shown is substantially the same.

I claim:

The ornamental design for a single spindle automatic metal working machine, substantially as shown and described.

ALFRED E. DRISSNER.
